UNITED STATES PATENT OFFICE

JAMES R. CALDER, OF HAMILTON, ONTARIO, CANADA.

RAILWAY-RAIL.

1,076,016.

Specification of Letters Patent.

Patented Oct. 21, 1913.

Application filed February 18, 1913. Serial No. 749,220.

To all whom it may concern:

Be it known that I, JAMES R. CALDER, of the city of Hamilton, in the Province of Ontario, Canada, have invented certain new 5 and useful Improvements in Railway-Rails.

This invention relates to rails particularly adapted for street railway use, and my object is to devise a rail in which the usual rail-connecting devices are dispensed 10 with and in which the rail head is detachable so that when worn it can be replaced without tearing up the road bed.

I attain my object by forming the rail in two parts namely; a base portion having 15 a socket formed longitudinally therein the inner face of one side wall of the socket being convexly curved and a head portion having a stem of less width than the socket fitted therein and having one side concavely 20 curved substantially concentric with the curve of the aforesaid wall of the socket. A curved filling piece is adapted to be fitted into the space between the said curved surfaces securely locking the two parts together. The bottom of the stem is normally 25 above the bottom of the socket so that the head may settle into place and automatically take up wear.

Figure 1 is a side elevation of part of a 30 track formed with my improved rail. Fig. 2 is a side elevation of the filling piece. Fig. 3 is a cross section of the same and Fig. 4 is an enlarged cross section of the rail.

In the drawings like numerals of reference indicate corresponding parts in the different figures.

The base portion 1 has the upper portion of its web enlarged and a socket 2 is formed therein extending lengthwise of the rail.

40 The inner face 3 of one wall of the socket is convexly curved and the opposite face 4 is preferably straight and inclined somewhat from the bottom inwardly.

The head 5 has a stem 6 formed thereon 45 of less width than the socket, one side of which fits the straight side of the socket while the other is curved substantially concentric with the curve of the curved side of the socket.

50 After the stem has been placed in the socket a curved filling piece 7 is fitted in between the curved surfaces. When this is

in place the head is securely locked to the base against displacement either upwardly or downwardly.

55

The parts are so proportioned that the bottom of the stem is normally above the bottom of the socket so that the stem may settle into place till all the parts are tight. Thus all looseness is avoided and any wear 60 is automatically taken up.

The parts of the rails are so laid that they break joint with one another and thus all special connections may be dispensed with.

65

To enable the filling piece to be pried out I provide holes 8 extending through the side of the socket below the filling piece. A lifting lever with a suitably shaped end may be inserted through these holes and engaged with the under side of the filling piece.

70

As the base of the rail need never be disturbed when once it is laid and as the top is easily removed without any tearing up of the road bed it is evident that the process of rail renewal is much simplified and cheapened, particularly as the renewal of heads is much cheaper than renewing a 75 complete rail.

80

It will also be found that the contacts are so extensive with such a rail that rail end welding and special bonding are rendered unnecessary.

What I claim as my invention is:—

85

1. A two-part rail comprising a base portion having a socket formed longitudinally therein the inner face of one side wall of the socket being convexly curved; a head portion having a stem of less width than the socket and fitted therein and having one side concavely curved substantially concentric with the curve of the aforesaid wall of the socket; and a curved filling piece adapted to be fitted into the space between the 90 said curved surfaces, the bottom of the said stem normally being above the bottom of the socket.

95

2. A two-part rail comprising a base portion having a socket formed longitudinally 100 therein the inner face of one side wall of the socket being convexly curved; a head portion having a stem of less width than the socket and fitted therein and having

one side concavely curved substantially concentric with the curve of the aforesaid wall of the socket; and a curved filling piece adapted to be fitted into the space between the said curved surfaces, the bottom of the said stem normally being above the bottom of the socket, and a hole being formed through the side of the base portion into

the socket for the introduction of a tool to pry out the filling piece.

Dated at Hamilton, Canada, this fourteenth day of February, 1913.

10 JAMES R. CALDER.

Signed in the presence of—

J. GEO. WEGENAST,
RICHARD BUTLER.
